UNITED STATES PATENT OFFICE

2,460,548

COMB

William L. Stewart, Fitchburg, Mass.

Application March 23, 1946, Serial No. 656,549

2 Claims. (Cl. 132—16)

1

This invention relates to new and useful improvements and structural refinements in combs, and the principal object of the invention is to provide a device of the character herein described, in which a novel structure of rotatable discs is employed in place of the conventional comb teeth. When in operation, the rotating discs will continually keep themselves clean and the unsanitary conditions resulting from the accumulation of dirt and other foreign matter on and between the conventional comb teeth will thus be eliminated.

A further object of the invention is to provide a comb in which the frictional contact between the discs may be readily and conveniently adjusted and which may be effectively employed for massaging purposes, if desired, at the same time that the hair is being combed.

An additional object of the invention is to provide a comb in which the discs have rounded peripheral edges for contacting the scalp, in place of the sharp pointed extremities usually provided at the ends of the comb teeth.

A still further object of the invention is to provide a comb in which any of the rotatable discs, when damaged, may be readily removed and replaced.

Another object of the invention is to provide a comb which is of simple construction, pleasing appearance, and which will lend itself to economical manufacture.

With the above more important objects in view, and such other objects as may become apparent as this specification proceeds, the invention consists essentially of the arrangement and construction of parts as illustrated in the accompanying drawings, in which—

Figure 1 is a side elevation of the invention, partially broken away.

Figure 2 is an end view taken in the direction of the arrow 2 in Figure 1.

Figure 3 is an end view taken in the direction of the arrow 3 in Figure 1.

Figure 4 is an elevation and a cross-sectional view of one of the finely-spaced discs.

Figure 5 is an elevation and a cross-sectional view of one of the coarsely-spaced discs, and

Figure 6 is a cross-sectional view taken in the plane of the line 6—6 in Figure 1.

Like characters of reference are used to designate like parts in the specification and throughout the several views.

Referring now to the accompanying drawings in detail, the invention consists of a back bar 10, having a substantially elliptical cross-sectional

configuration and formed at the ends thereof with the integral, laterally projecting end-pieces 11.

The back bar together with the end-pieces define a holder designated generally by the reference character 12, and the end-pieces 11 are formed with a pair of aligned apertures 13. A shaft 14 is journaled in these apertures, one end of this shaft being provided with the head 15, while its remaining end is formed with the screw-threaded portion 16 adapted to receive the adjusting wing nut 17.

A plurality of rotatable discs designated generally by the character 18 are positioned on the shaft 14, each of these discs consisting of a circular plate 19 formed with the rounded peripheral edge 20, and provided on both sides with the concentric, frusto-conical bosses 21. These bosses may be formed integrally with the plate 19, and the disc as a whole is formed with a central aperture 22, whereby it may be positioned on the shaft 14.

With particular reference to the accompanying Figure 1, it will be noted that the discs 18 on the left side of the comb are spaced closer together as compared to the discs 23 on the right side. This arrangement is in conformity with fine and coarse teeth usually provided in the conventional comb, and is achieved by lengthening the frusto-conical bosses 24 of the discs 23, as compared to the bosses 21. In this manner, the discs 18 when assembled, will be spaced in a relatively closer relationship with respect to the discs 23, as will be clearly apparent from the accompanying drawings.

When the invention is placed in use, the comb is used in the conventional manner by drawing the same through the hair and the frictional contact between the several discs may be adjusted by turning the wing nut 17. If desired, this adjustment may be slackened sufficiently to permit unrestricted rotation of the discs, whereupon the comb may be used for massaging purposes.

When any of the discs become damaged or broken, the same may be replaced by simply removing the wing nut 17 and withdrawing the shaft 14 from the end-pieces 11 and replacing the affected disc or discs.

While in the foregoing there has been shown and described the preferred embodiment of this invention it is to be understood that minor changes in the details of construction, combination and arrangement of parts may be resorted to without departing from the spirit and scope 55 of the invention as claimed.

What I claim as my invention is:

1. A comb comprising, in combination, a back bar and laterally projecting end-pieces defining a holder, a shaft journalled in said end-pieces, a head at one end and a screw-threaded portion at the remaining end of said shaft, an adjusting knob on said screw-threaded portion, a plurality of rotatable discs each comprising a circular plate formed with a rounded peripheral edge, and a concentric, frusto-conical boss formed integrally on each side of said plate, said discs being formed with central apertures adapted to rotatably receive said shaft, and the adjustment of said knob varying the frictional contact between said discs.

2. The device as defined in claim 1, in which

said discs at one side of said comb are spaced in a relatively closer relationship with respect to the discs at the remaining side of said comb.

WILLIAM L. STEWART.
